J. E. OLIVER

ACCELERATOR FOOT REST

Filed Sept. 4, 1923

UNITED STATES PATENT OFFICE.

JOEL E. OLIVER, OF SANTA BARBARA, CALIFORNIA.

ACCELERATOR FOOT REST.

Application filed September 4, 1923. Serial No. 660,899.

To all whom it may concern:

Be it known that I, JOEL E. OLIVER, a citizen of the United States, residing at Santa Barbara, in the county of Santa Barbara and State of California, have invented Accelerator Foot Rests, of which the following is a specification.

This invention relates to a motor vehicle accelerator pedal foot rest.

10 The primary object of this invention is to provide a foot rest adapted to engage the accelerator pedal of the motor vehicle for the operation thereof.

15 A further object is to provide a foot rest for an accelerator pedal with no permanent connection between the foot rest and the accelerator pedal.

20 This invention also consists in certain other features of construction and in the combination and arrangement of the several parts, to be hereinafter fully described, illustrated in the accompanying drawings and specifically pointed out in the appended claim.

25 In describing my invention in detail, reference will be had to the accompanying drawings wherein like characters denote like or corresponding parts throughout the several views, and in which:

30 In the drawings:

Figure 1 is a top plan view of the foot rest showing the top plate thereof knurled in the form of pyramids.

Figure 2 is a side view of the foot rest.

35 Figure 3 is a bottom plan view thereof.

Figure 4 is an end view showing its means of connection with the floor board of the vehicle.

Referring now to the drawings in detail, 40 the reference numeral 1 indicates the top plate which has its top or foot engaging portion provided with pyramid shaped projections 2 arranged to cover its entire surface with the exception of the marginal edge 3. Depending from each side of the plate 1 slightly beyond the center there are a pair of spaced apertured ears 4 adapted to cooperate with like shaped apertured ears 5 right angled disposed with respect to the base plate 6 and rising therefrom, the base plate 6 is provided with end openings 7 to receive countersunk screws 8 in securing said base plate to the floor of a motor ve-

hicle in juxtaposition to the accelerator pedal (not shown). A headed pin 9 passes through the ears of the respective plates, in a manner to provide bearing surfaces for the aperture whereby the top plate is pivotally associated with the base plate, as clearly shown in Figure 4 of the drawings. The 55 pin is threaded at one end and receives a nut 10 for retaining said plate in operative position.

Riveted as at 11 to the base plate, there is one end of the leaf spring 12 which curves 60 upwardly from its connecting point and engages the bottom of the top plate adjacent one end with its free end terminating in a downturned portion 13.

From the above and the structure, as 65 shown in the drawings, it will be apparent that the foot rest is extremely simple and positive in operation, and the spring engaged end 14 thereof is adapted to contact the conventional type of accelerator pedal 70 for the operation thereof. The top plate 1 being knurled, as shown, will make it practically impossible for the operator's foot to casually slip therefrom and by said plate being pivoted through the medium of the 75 pin 9 passing through the apertured ears, it can be readily rocked against the tension of the spring 11 which will endeavor to retain it in its normal position.

It is thought from the foregoing description that the advantages and novel features of my invention will be readily apparent.

I desire it to be understood that I may make changes in the construction and in the 80 combination and arrangement of the several parts, provided that such changes fall within the scope of the appended claim.

Having thus described my invention, what I claim is:—

95 A foot rest of the character described comprising a top plate having a knurled upper surface, a pair of apertured ears each depending from the side edges of the top plate and being arranged slightly beyond its central portion, a base plate provided with end openings, screws countersunk in said openings for securing said base plate in fixed position, apertured ears rising from the ears of said base plate and being associated with 100 105 apertured ends of the top plate in a manner

whereby the apertures register, a headed pin passing through the registered apertures for pivotally mounting said plates, a spring having one end riveted to the base plate midway its ends and from its connection said spring curves upwardly to engage the top plate adjacent their end remote from its

pivot point and said last mentioned end of said top plate being adapted to engage an accelerator pedal as and for the purpose 10 specified.

In testimony whereof I have signed my name to this specification.

JOEL E. OLIVER.
